UNITED STATES PATENT OFFICE

HARRY C. WASSON, OF FRANKLIN, PENNSYLVANIA, ASSIGNOR TO CHICAGO PNEUMATIC TOOL COMPANY, OF NEW YORK, N. Y., A CORPORATION OF NEW JERSEY

SAFETY STOP APPARATUS FOR ENGINES

Application filed April 20, 1929. Serial No. 356,648.

This invention relates to that general class of prime movers which have force feed circulation of a medium adapted to lubricate or to cool the engine.

One object of the invention is to provide apparatus which will automatically operate to stop the engine in the event of failure or serious impairment of the circulating system. Another object is to make such apparatus 10 simple and readily applicable to old as well as to new engines. Further objects will be apparent from the detailed description which follows.

In order to illustrate the invention one 15 concrete embodiment thereof is shown in the accompanying drawings, in which:

Fig. 1 is a side elevational view of an engine driven unit;

Fig. 2 is a right end elevational view; and 20 Fig. 3 is an enlarged vertical sectional view of the control device.

The invention is illustrated as embodied in an engine driven compressor unit comprising an internal combustion engine indicated generally at A with cylinders a which is arranged to drive a pump or compressor B.

The engine and the pump may be of any suitable or desired type and in the present instance are shown as mounted upon the same 30 base C. The motive agent for engine shown is manufactured or natural gas which is fed into the same through a pipe a¹ which connects with a mixing valve or device a² to provide the explosive charges for cylinders a.

35 The unit is arranged to be suitably lubricated by a force feed system which includes a pump p (Fig. 1) located in the oil sump and the unit may also have a force feed cooling system. Since the details of the engine unit 40 form no part of the present invention further description thereof is omitted.

The invention involves the utilizing of the pressure in a force feed circulating system of the engine for automatically cutting off the fuel supply when the pressure falls below 45 a predetermined minimum. To this end a gravity operated control valve 4 is provided in the fuel conduit a¹ conveniently adjacent a mixing valve a². As indicated in the enlarged 50 sectional view (Fig. 3) of the control valve,

it comprises a casing 5 having a base 6 with a transverse partition 7 provided with a port 7a arranged to be controlled by a valve proper 8 mounted upon a reciprocating stem or plunger 9. A lever 10 pivoted at 10a to casing 5 extends through a slot 9a in an enlargement of plunger 9 and normally forces valve 8 upwardly to closed position through the action of a weight 11 secured to lever 10 in adjusted position by a screw bolt 12. Plunger 60 9 has an enlarged head 9b in contact with diaphragm 13 forming a part of a fluid tight chamber provided by an enlargement 5a of casing 5. A pipe or conduit 14 subjects the upper part of diaphragm 13 to the pressure 65 obtaining in the force feed lubricating system. Conduit 14 issues from crank case C as indicated in Figs. 1 and 2 and may have therein a gauge 15 to indicate to the operator the amount of pressure in the lubricating 70 system.

From the above it will be apparent that when the engine unit is not in operation or when the pressure in the lubricating system falls below the pressure predetermined by 75 the adjustment of weight 11 on lever 10, weight 11 will move valve 8 upwardly to closed position and close off the fuel supply admitted through inlet pipe a¹. In starting the engine pressure may be built up in the 80 lubricating system through the use of a hand pump (not shown) or lever 10 may be suitably secured temporarily in a position to open valve 8. With the engine in operation and normal pressure in the lubricating system the force exerted by such pressure on diaphragm 13 and head 9b of the valve plunger will overcome the gravity control of lever 10 by weight 11. A drop in pressure 85 in the lubricating system which might 90 mean damage to the engine will effect a positive closing off of the fuel supply and stop the engine until the trouble is remedied.

While the invention has been herein disclosed in what is now considered to be its 95 preferred form, it is to be understood that the invention is not limited to the specific details thereof, but covers all changes, modifications, and adaptations within the scope of the appended claims.

I claim as my invention:

1. The combination with a prime mover having a force feed circulating system, of a conduit for the motive agent leading to said engine, a valve for closing said conduit including a plunger carrying the valve proper, a lever having an adjustable weight for moving said plunger to valve closing position, and means utilizing the pressure in said circulating system to counteract the action of said weight.
2. The combination with a prime mover having a force feed circulating system, of a conduit for the motive agent leading to said engine, a valve for closing said conduit including a plunger carrying the valve proper, a lever having an adjustable weight for moving said plunger to valve closing position, and means including a diaphragm for utilizing the pressure in said circulating system to counteract the action of said weight.
3. The combination with an internal combustion engine having a force feed lubricating system, of a fuel conduit, a valve for closing said conduit, a plunger to which said valve is secured, a lever for actuating said valve to closing position, a weight adjustably disposed on said lever, an enlarged head on said plunger, a casing including said plunger head, a diaphragm in said casing in engagement with said head, and a connection to said casing from said force feed system for making the pressure in the latter effective through said diaphragm and plunger to overcome said weight and hold said valve open so long as said pressure exceeds a predetermined minimum.

Signed by me at Franklin, in the county of Venango and State of Penn., this 17th day of April, 1929.

HARRY C. WASSON.
